[57] CLAIM

The ornamental design of a bottle carrier, as shown and described.

DESCRIPTION

FIG. 1 is a top plan view of my new design for a bottle carrier, the opposite side being a mirror image thereof; and, FIG. 2 is a perspective view, shown at a reduced scale, of the bottle carrier, the long side that is not shown being a mirror image of the long side that is shown.

The broken line showing of a bottle is for illustrative purposes only and forms no part of the claimed design.
